UNITED STATES PATENT OFFICE.

ARTHUR J. FREEMAN, OF PETALUMA, CALIFORNIA.

SHEET-CONVEYER.

1,133,630.

Specification of Letters Patent.

Patented Mar. 30, 1915.

Application filed July 15, 1913, Serial No. 779,121. Renewed October 19, 1914. Serial No. 867,533.

To all whom it may concern:

Be it known that I, ARTHUR J. FREEMAN, a citizen of the United States, residing at Petaluma, in the county of Sonoma and State of California, have invented new and useful Improvements in Sheet-Conveyers, of which the following is a specification.

This invention relates to a sheet carrier or conveyer, and particularly pertains to an apparatus for delivering sheet material, such as paper and the like, one sheet at a time, to a printing or other apparatus.

It is the object of this invention to provide a mechanism which is particularly adapted for use in connection with photo printing machines, such as shown in Patent No. 1,036,212, issued to me August 20, 1912, and which apparatus is so constructed as to pick up and remove a single sheet from a stack and deposit it in a printing position.

Another object is to provide an automatic mechanism of the above character in which the positioning of the sheet to be printed will be rendered accurate and exact, so that each consecutive sheet will be printed uniformly.

A further object is to provide a simple and efficient means for picking up and discharging the sheets, one at a time.

The invention primarily resides in a pump-operated suction cup carried on a swinging arm and mechanism controlling the movement of the arm and operation of the suction cup, whereby the latter will be caused to pick up a sheet of material when the arm is in one position and hold the sheet while the arm is in motion, then release the sheet when the arm is in another position.

The invention further consists of the parts and the construction and combination of parts as hereinafter more fully described and claimed, having reference to the accompanying drawings, in which—

Figure 1 is a view of the invention in side elevation with parts broken away, showing the carrier arm disposed in the delivering position in full lines, and in its receiving position in dotted lines. Fig. 2 is an enlarged detail section and elevation of the suction cup on the line $a-a$ of Fig. 1. Fig. 3 is a plan view. Fig. 4 is an enlarged detail plan view of the pivoted end portion of the carrier arm. Fig. 5 is a detail in plan of the outer end of the carrier arm, illustrating the positioning of the suction

cup in picking up a sheet. Fig. 6 is a view in diagram of the cam employed in actuating the carrier arm.

In the drawings A represents a carrier or conveyer arm which is pivoted at 2 to a yoke 3, swiveled on a pivot pin 4; the arm A being thus adapted to have a horizontal or rocking outward movement on the pivot 2 and a vertical movement on the pivot pin 4. In the present application of the invention I have shown the invention as adapted to operate in relation to a vertical wall B in which the pivot pin 4 is mounted, but it will be manifest that the device will operate on either an inclined or flat surface. The arm A is normally maintained in an innermost position approximately parallel with the face of the partition B by means of a torsion spring 5, one end of which is rigidly secured to the swiveled yoke 3, while the other end is engaged with the arm A, as particularly shown in Fig. 4.

Mounted on the outer end of the arm A is a bracket 6 which extends inwardly toward the wall B and is attached to the arm A by means of a bolt 7 and nut 8; the bracket 6 being adapted to be adjusted at various angles in relation to the arm A by means of the bolt 7 and nut 8.

Pivoted at 9 on the outer end of the bracket 6 is a block 10 in which a tubular stem 11 is adjustably mounted. The stem 11 terminates at one end a short distance from the block 10 and has a suction cup 12 formed of suitable resilient material mounted thereon; a perforation 13 being formed centrally of the suction cup 12 to provide a communication between the inner face of the cup 12 and the interior of the tubular stem 11. The outer portion of the stem 11 terminates adjacent to the arm A and connects with a flexible tube 14 which is supported by the arm A and leads to and terminates in the lower end of a vertically-disposed cylinder 15.

Reciprocally mounted in the cylinder 15 is a piston 16 on a piston rod 17, which extends upward from the cylinder 15 and has a lateral projection 18 adjacent to its upper end, which projection is engaged by a vertically-disposed disk cam 19, mounted on a revoluble shaft 20, supported in suitable bearings in the wall B, and adapted to be rotated continuously from any suitable source of power. The piston 16 is designed to be moved in an upward direction by the

action of the cam 19 on the projection 18, thereby creating a suction in the lower portion of the cylinder 15 on the upward movement of the piston; the latter operating on its up-stroke to draw air through the tube 14, stem 11 and projection 13 from the inner side of the suction cup 12. The cam 19 is so shaped as to move the piston 16 in an upward direction, one stroke to each revolution of the cam. A spring 21 having one end rigidly attached at 22 to a rigid support and its other end connecting with the piston rod 17 operates to normally maintain the piston rod 17 in its lowermost position and serves to move the piston rod 17 on its down stroke when it is relieved from the upward throw of the cam 19.

Mounted on the shaft 20, in front of the cam 19, is a cam 23 for operating the carrier arm A. The cam 23 is of the groove type and is adapted to rock the arm A horizontally in conjunction with the spring 5 and to independently swing the arm A in a vertical direction. The groove 24 of the cam 23 is arranged on its vertical face and is substantially pyriform in outline and arranged eccentric to the shaft 20. A pin or projection 25 on the arm A extends into the cam groove 24 and is normally held in engagement therewith by means of the spring 5. The pin 25 is formed with a shoulder 26 which bears on the outer edges of the cam groove 24, which are so shaped as to rock the arm A on the pivot 2 when the cam 23 is rotated. The contour of the face of the cam 23 is illustrated in Fig. 6, and comprises a low or starting point b connecting with an inclined portion c and terminating in an elevated portion d, ending in a depressed or low portion e, from which an outwardly inclined portion f leads and terminates in a raised portion g, substantially on a plane with the raised portion d; the portion g terminating in an inwardly inclined portion h, leading back to the starting portion b.

Pivottally connected to the outer end of the stem 11 is a link 27, which normally extends approximately parallel with the arm A and is pivoted at 28 at its opposite end to an arm 29, pivoted at 30 to the yoke 3. A plate spring 31 mounted on the yoke 3 bears against the arm 29 adjacent to its outer end and normally retains the latter in an innermost position against a stop-pin 32 on the yoke 3. The spring 31 is of sufficient tension to overcome the friction of the pivot 9. The pivotal connection 28 of the link 27 is so disposed in relation to the pivot 2 on the arm A that on the outward and inward movements of the arm A, the stem 11 will be rocked on the pivot 9 so that the cup 12 will travel in substantially a due line at right angles to the face of a negative or plate F, carried in an adjustable support or frame G, mounted on the partition B, and

to the stack of sheets C on the rack D. The outer end of the arm 29 is bent at right angles to extend alongside of the link 27 and is formed with a lug 33, having a set screw 34 mounted therein; the stem of the set screw 34 being disposed in alignment with the outer side of the link 27 and adapted to be moved toward and away from the link 27 by turning it in its threaded bearings. The end of the set screw 34 is designed to be spaced a short distance from the link 27, as shown in Fig. 4, the distance separating the set screw from the link being varied as occasion may require.

In the operation of the invention when the arm A is in its lowermost position, as indicated in dotted lines in Fig. 1, the suction cup 12 will be disposed in contact with a sheet of material of any desired character, indicated at C, which is carried in a suitable adjustable rack D, mounted on the wall B; a stack of sheets C of any desired number being disposed in the rack D and temporarily held in place therein by means of spring-pressed fingers E which extend inwardly a short distance over the edges of the sheets C. When the arm A is thus positioned, the piston 16 will be disposed in its lowermost position in the cylinder 15, in which position it is maintained by the action of the spring 21. On the initial rotation of the shaft 20 the cam 19 will operate on the projection 18 in such manner as to elevate the piston rod 17 in opposition to the spring 21, thereby moving the piston 16 in an upward direction in the cylinder 15. This action serves to draw the air from the inner side of the suction cup 12, which lies in close contact with a sheet C, thereby creating a suction sufficient to affix the sheet C to the cup 12. During this operation the cam 23 will be so disposed that the pin 25 will be disposed in a portion of the cam groove 24, arranged concentric with the shaft 20, so that the arm A will momentarily remain stationary; the shoulder b on the cam 23 being positioned adjacent to the shoulder 26 on the pin 25, so that the arm A will be in its lowermost position. As soon as the cam 19 has moved sufficiently far to create sufficient suction in the cup 12 to cause the latter to pick up a sheet C, the cam 23 on rotating will move so as to cause the cam face c to engage the shoulder 26 on the pin 25 and move the outer end of the arm A in an outward direction, carrying the sheet C therewith, the latter being lifted out of engagement with the spring-pressed fingers E which operate to engage the sheet immediately behind the one being removed, to prevent more than one sheet being picked up by the cup 12 at one time. Continued rotation of the cam 23 will cause the arm A to be moved upward simultaneously with its outward movement, and when the shoulder 130

26 rides over the raised cam face *d*, into the depressed portion *e*, the arm A will be disposed in its uppermost and innermost position, as indicated in full lines in Fig. 1. 5 On the inward movement of the arm A in its uppermost position the stem 11 will be rocked on its pivot 9 by the use of the link 27 in such manner as to dispose the suction cup 12 and the sheet C thereon parallel 10 with the negative or plate F, so that the sheet C will be carried flat against the plate F.

When the sheet C has been placed against the plate F and engaged by a mechanism, 15 not necessary to be here shown, the cam 19 will be so disposed as to allow the spring 21 to quickly restore the piston 16 to its normal lowermost position, thereby breaking the suction of the cup 12 and causing the latter to release the sheet C. The cam face *f* on the cam 23 will then operate to move the arm A outwardly, as indicated in dotted lines in Fig. 3; the suction cup 12 moving away a short distance from the sheet C, parallel therewith, by reason of the link 27 rocking on the pivot 28. The moment the link 27 contacts the set screw 34 its rocking movement on the pivot 28 will be prevented, and the continued outward movement of the outer end of the arm A will cause the link 27 to rock the arm 29 on the pivot 30 in opposition to the spring 31, thus disposing the stem 11 in an inclined position. The shoulder 26 on the pin 25, on riding over the 30 portions *g* and *h* of the cam 23, will allow the spring 5 to operate to restore the arm A to its lower, innermost position; the suction cup 12 moving into contact with a sheet C at an angle, as shown in Fig. 5. The flexible 35 nature of the suction cup 12 permits its inner face being moved into contact with the surface of the sheet C, as indicated in dotted lines in Fig. 5, so that when the piston 16 is again reciprocated in an upward direction the suction cup 12 will be caused to annex another sheet C. This flexure of the suction cup 12 is important, as it compensates for the fact that the cup is not at all times parallel with the sheets C in the rack 40 D, or the plate F. The rocking of the stem 11 on the pivot 9 compensates for the varying thickness of the stack of sheets C and the arcual movement of the outer end of the arm A in relation thereto. By adjusting 45 the set screw 34 the angle of inclination of the stem 11, carrying the cup 12, may be varied as occasion may require to advance or retract the position of the suction cup 12 in relation to the vertical face of the sheets 50 C. The levers connected with the suction cup are provided for the purpose of causing it to move in a due line at right angles with the partition B and sheets C, and to cause it to pick up the first or top sheet 55 when the sheet holder D is full, in exactly

the same place as all succeeding sheets. By varying the speed of rotation of the shaft 20 and the cam 23, the sheets C may be picked up from the stack on the rack D and delivered to the plate F at any desired interval of time. 70

From the foregoing it will be seen that by rotating the shaft 20 the outer end of the arm A will be caused to travel from its lower, innermost position upwardly and inwardly, thence back to its initial position over approximately the same path on each rotation of the shaft 20. 75

It is manifest that while I have described the apparatus as applied to a photo printing machine, it is equally applicable for use in other mechanisms where it is desirable to deliver sheet material, one sheet at a time, at intervals. 80

Having thus described my invention, 85 what I claim and desire to secure by Letters Patent, is:

1. In a sheet conveyer, an arm, a member mounted to have vertical rocking movement, means to pivotally connect one end of said arm to said member whereby the arm may have horizontal reciprocatory movement on said pivot, an angularly disposed bracket adjustably connected to the opposite end of the arm, an element pivotally mounted on 95 the bracket, a tubular stem adjustably connected to said element, a suction cup on the stem, a link connected at one end to said stem and at its opposite end to said member, a shouldered pin on said arm, a cam having 100 a groove into which the pin extends and a raised portion which engages with the shoulder of the pin, and means to create a vacuum in the tubular stem. 105

2. In a sheet conveyer, an arm, a member mounted to have vertical rocking movement, means to pivotally connect one end of said arm to said member whereby the arm may have horizontal reciprocatory movement on said pivot, a suction cup pivotally connected to one end of the arm, a link in connection with said cup at one end, means to pivotally connect the opposite end of the link to said member, means carried by the second named means, to limit the extent of movement of the link relative to said second named means, means to create a vacuum in the cup, and means to impart vertical and horizontally reciprocatory movement to the arm. 110 115

3. In a sheet conveyer, an arm, a member mounted to have vertical rocking movement, means to pivotally connect one end of said arm to said member whereby the arm may have horizontal reciprocatory movement on said pivot, a suction cup pivotally connected to one end of the arm, a spring tensioned right angular arm pivoted at one end to said member, a link having one end in connection with said cup, the opposite end of said link 120 125 130

5 being pivotally connected to the angle of said right angular arm, means borne by the opposite end of the right angular arm to adjustably engage the link, means to impart vertical and horizontal reciprocatory movement to the first named arm, and means to create a vacuum in said cup.

6. In a sheet conveyer, an arm, a suction cup movably connected to the outer end of 10 said arm, a member to which the opposite end of the arm is pivoted, means to revolvably mount said member, a link having one end in connection with said cup, and means pivotally connected to the opposite end of 15 said link and to said member to allow the link to initially move independently of said second mentioned means and about the pivotal connection between said link and second mentioned means and to then upon continued movement to cause the second mentioned 20 means to move with the link and about the pivotal connection between said second mentioned means and member.

5. In a sheet conveyer, an arm, a member 25 mounted to have vertical rocking movement, means to pivotally connect one end of said arm to said member whereby the arm may have horizontal reciprocatory movement on said pivot, a suction cup movably 30 connected to the opposite end of the arm, a link having one end in connection with said cup, a spring pressed element pivotally con-

nected to the other end of the link and to 35 said member, means to rock the arm vertically and horizontally, and means whereby said link after predetermined horizontal movement about its said pivotal connection with said element will engage the element and move therewith about the pivotal connection of the element with said member. 40

6. In a sheet conveyer, a revoluble member, an arm pivoted thereto and having a suction cup on its free end, a cam having a groove and a raised portion, and means on the arm to both engage in said groove and to 45 also engage with the raised portion of the cam to vertically and horizontally reciprocate said arm.

7. In a sheet conveyer, a revoluble member, an arm pivoted thereto and having a 50 suction cup on its free end, a cam having a groove and a raised portion, and a shouldered pin carried by said arm, said pin projecting in the cam groove and the shoulder thereof engaging the raised portion of 55 the cam to vertically and horizontally reciprocate said arm.

In testimony whereof I have hereunto set my hand in the presence of two subscribing witnesses.

ARTHUR J. FREEMAN.
